Inventor:

George Gordon Frater

*By Ira M. Jones
Attorney*

UNITED STATES PATENT OFFICE.

GEORGE GORDON FRATER, OF WATERTOWN, WISCONSIN, ASSIGNOR TO G. B. LEWIS COMPANY, OF WATERTOWN, WISCONSIN, A CORPORATION OF WISCONSIN.

BEEHIVE FRAME.

Application filed August 4, 1922. Serial No. 579,641.

To all whom it may concern:

Be it known that I, GEORGE GORDON FRATER, a citizen of the United States, and resident of Watertown, in the county of Jefferson and State of Wisconsin, have invented new and useful Improvements in Beehive Frames, of which the following is a description, reference being had to the accompanying drawing, which is a part of this specification.

This invention relates to certain new and useful improvements in bee hive appliances, and refers more particularly to a hive frame adapted for use in connection with wire brood foundations.

When bees cluster on the foundation, the heat of their bodies results in the stretching or expanding thereof, and in the event this stretch or expansion is not accommodated, the foundation buckles producing what is termed a drone comb. Having this in mind, it is one of the objects of this invention to provide means for securing a foundation within the frame in such a manner as to accommodate the expansion or stretching of the foundation and thus eliminate buckling thereof.

In the type of frames now commonly employed, it is impossible to completely fill the frame with a sheet of foundation without causing defects in the comb produced and a further object of this invention resides in the provision of means whereby a sheet of foundation may be secured in the frame to completely fill the same.

A still further object of this invention resides in the provision of a slotted bottom bar for a hive frame in which the lower end of the foundation is disposed to freely permit its stretching or expansion without buckling of the foundation.

With the above and other objects in view which will appear as the description proceeds, my invention resides in the novel construction, combination and arrangement of parts substantially as hereinafter described and more particularly defined by the appended claim, it being understood that such changes in the precise embodiment of the herein disclosed invention may be made as come within the scope of the claim.

In the accompanying drawing, I have illustrated one complete example of the physi-

cal embodiment of my invention constructed according to the best mode I have so far 55 devised for the practical application of the principles thereof, and in which:

Figure 1 is a view of the lower portion of a frame embodying my invention, a part thereof being broken away to more clearly 60 illustrate details of construction, and

Figure 2 is a top view of the improved bottom bar detached from the frame.

In the bee industry, it is desirable to provide sheet foundations for the combs and in practice much difficulty has been experienced in so mounting the comb foundation as to completely fill the space of the frame and at the same time eliminate buckling when any 70 number of bees cluster thereon, as either their weight stretches the foundation or the heat of their bodies causes the expansion thereof. As a result of this buckling, imperfect combs are produced and consequently 75 much loss occasioned.

In the drawing is illustrated a frame structure which experience has proven completely compensates or accommodates for all stretching of the foundation which is illustrated as consisting of a sheet of comb foundation 5 reinforced at intervals by heavy 80 wires 6 and secured in a frame 7 including side, top and bottom bars 8, 9 and 10, respectively.

In this invention, the bottom bar 10 is 85 formed from a single strip of material and has a central, longitudinal slot 11 extending throughout substantially the entire length thereof into which the lower end of the foundation is projected. The foundation is 90 properly secured to the side and top bars and by reason of the lower end being free, any expansion or stretching is accommodated, as will be readily apparent to thus 95 eliminate any buckling of the foundation to thus insure the production of perfect combs.

From the foregoing description, taken in connection with the accompanying drawing, it will be readily obvious to those skilled in the art to which an invention of this character appertains that, by suspending the foundation sheet within the frame with its lower edge disposed in a slot formed in the bottom bar, but free thereof, buckling of the foundation sheet due to expansion or 105 stretching is prevented; and that means is

provided for attachment by the bees of the foundation sheet to the frame as they build up the comb after the foundation sheet has fully stretched or expanded, so that the frame with the comb therein may be readily handled without fear of damage.

What I claim as my invention is:

A device of the character described, comprising a frame including top, bottom and

side bars, the bottom bar having a slot cut therein throughout the inside length of the frame and a foundation suspended from the top bar with its lower end hanging freely in the bottom bar slot, whereby expansion of the foundation is accommodated.

In testimony whereof I affix my signature.

GEORGE GORDON FRATER.
